COMBINED COVER AND SUCTION PRODUCING APPARATUS FOR VACUUM CLEANERS OR THE LIKE

Richard C. Medley, Niles, Ill., assignor to Breuer Electric Mfg. Co., Chicago, Ill., a corporation of Illinois

Continuation of design applications Ser. Nos. 73,312, 73,313, and 73,314, Jan. 25, 1963. This application Aug. 13, 1964, Ser. No. 81,269

Term of patent 14 years

(Cl. D9—2)

FIGURE 1 is a top plan view of a combined cover and suction producing apparatus for vacuum cleaners or the like showing my new design;

FIGURE 2 is a front elevational view thereof;

FIGURE 3 is an elevational view of one side thereof;

FIGURE 4 is an elevational view of the opposite side thereof;

FIGURE 5 is a top plan view of a second embodiment of the design shown in FIG. 1;

FIGURE 6 is a front elevational view thereof;

FIGURE 7 is an elevational view of one side thereof;

FIGURE 8 is an elevational view of the opposite side thereof;

FIGURE 9 is a top plan view of a third embodiment of the design shown in FIGURE 1;

FIGURE 10 is a front elevational view thereof;

FIGURE 11 is an elevational view of one side thereof; and

FIGURE 12 is an elevational view of the opposite side thereof.

The perforations in the cylindrical elements in the several views are continuous around the circumference of the element in the area between the dotted lines.

This application is a continuation of my copending applications Serial Nos. D-73,312, D-73,313 and D-73,314, filed January 25, 1963, now abandoned.

I claim:

The ornamental design for a combined cover and suction producing apparatus for vacuum cleaners or the like, substantially as shown and described.
